AXIAL THRASHING AND STRAW REDUCING MACHINE

Application filed February 23, 1929, Serial No. 342,175, and in Austria February 20, 1928.

This invention relates to an axial thrashing machine, or thrashing and straw-reducing machine, its object being to effect certain improvements in the device for separating the grain from the straw.

Machines of the kind referred to have the peculiarity of discharging the materials in a plurality of separate streams issuing one behind another along the machine drum. 10 This is particularly the case with machines of the Schlayer type, wherein, owing to the special arrangement of the rotary beaters and stationary abutments, the materials are first subjected to a lenient treatment which 15 discharges the loose and heavy grains, the thrashing being gradually intensified as the materials travel through the drum at the end of which the straw is torn and reduced.

In contradistinction to known constructions wherein the materials are discharged together in a single stream and require spacious devices and a considerable expenditure of power for a subsequent separation and dressing, the present invention consists in 25 providing a dressing or separating device for the differently conditioned streams of materials, said device separately treating these streams of materials. After the different streams have thus been subjected to 30 a substantially uniform preliminary dressing, they are preferably collected and subjected together to a final dressing. The invention allows the grain to be separated from the extraneous matter in a much more 35 economical manner than before.

The particularly advantageous construction of the machine is obtained by arranging the blower of the winnowing device parallel or nearly so to the longitudinally 40 disposed thrashing and straw-reducing drum. The grain dressing can then be carried out almost entirely by means of the wind from the blower the function of the sieves being principally to obstruct the falling movement of the materials and prolong 45 the action on the latter of the wind. When the materials issue from the drum the lighter parts thereof will immediately be caught by the wind and carried away. As compared with machines wherein the blower is

arranged transversely beneath or behind the drum, the novel blower arrangement has the further advantage that the machine can be built much lower and shorter and that it can thus be more easily supervised. 55

Naturally the more the wind gains in importance in the dressing of the materials, the greater will be the effect of variations in the strength of the same. Care must therefore be taken to maintain a constant 60 speed of the beater shaft. This can easily be effected by rendering the feed uniform.

Since the drum of an axial thrashing machine, unlike the ledge and spike drum machines, does not possess any feed regulating 65 cage which prevents the entrance of thick bundles of material, it is evident that a careless feeding will result in irregular movement of the machine. Such irregularity has a detrimental effect on the generation of 70 wind and thus on the functioning of the winnowing device. It is therefore necessary to provide means for rendering the feed uniform and this is effected by the provision of a regulator which evens out thick bundles 75 into thin uniform layers. This regulator consists of a box-shaped automatic feeder containing a conveying device comprising a rapidly moving endless band and a retarding element arranged under said band. 80

Fig. 1 of the accompanying drawings represents a longitudinal section of the machine.

Fig. 2 shows a plan of the same,

Fig. 3 is a rear view of the machine,

Fig. 4, a cross-section on the line IV—IV of Fig. 2,

Fig. 4a shows a blower mouth in section on an enlarged scale,

Fig. 5, a cross-section on the line V—V of Fig. 2.

1 is an axial thrashing and straw-reducing machine of the Schlayer type, wherein the rotating beaters 3 fixed to the beater shaft 2, are at the inlet end at a certain radial distance from the fixed abutments 5 arranged on the machine casing 4, the distance becoming smaller and smaller towards the discharge end of the machine where they intermesh for the reduction of the straw. I de- 100

notes the thrashing zone, II the preliminary reducing zone, III the final reducing zone, and IV the short straw outlet.

The machine drum 4 is carried by frame 6 which rests on removable running wheels 7 and is provided in its lower portion with adjustable feet 8 on which the machine stands during operation. On a front and middle transverse portion of the frame 6 there are bearings 9 for the beater shaft 2 which carries on its front end the driving belt pulley 10 and on its rear end a preferably axially adjustable disc 11. The latter allows the chopped straw to issue between its somewhat conically shaped rim and the wall of the final reducing chamber, whilst it has on the hub a concentric opening for admitting the additional air which is interrupted only by the spokes of the disc. This additional air flows to the hub opening from the rear end of the machine through a cylinder-like attachment 12 which passes through the hood 13 surrounding the short straw outlet.

The feed trough 14 is located laterally of the thrashing drum. On the same side of the machine and parallel to the thrashing and reducing drum 4 there is arranged the blower for the winnowing device, the bearing 15 for the blower shaft 16 being fixed on the side portions of the frame through the intermediary of small stands. The blower is formed of two co-axially arranged single blowers 17, 18, lying one behind the other, the wind-vanes 19 of which are all mounted on the shaft 16. The front blower portion 17 extends from a position somewhat behind the front wall of the machine up to the end of the final reducing chamber III. The second blower portion extends somewhat from the first third part of the hood 13 up to the rear transverse portion of the frame 6 located at a certain distance from the hood. The blower shaft 16 is connected with the beater shaft 2 by belt drive 20.

Beneath the thrashing and reducing drum 4 and stretching towards the side turned to the blower 17, there is located a preliminary winnowing mechanism 21 which consists of two oppositely moved shaking boxes and which is suspended in front on springs 22 and behind on reciprocating levers 22¹ and executes a movement which is transverse to the machine drum and which is imparted to the swinging levers 22¹ by the blower shaft 16 by means of connecting rods 23. From the sectional representation in Fig. 4, it is seen that the air issuing from the passage 24 (formed of adjustable walls) of the blower portion 17 aerates regularly both shaking boxes and can act directly especially on the stream of material which is winnowed and which issues from the discharge opening at the bottom and longitudinally of the drum 4.

As may be seen from the special repre-

sentation in Fig. 4a, there is located in the discharge portion of the not very short passage 24, a triangularly shaped regulating plate 24¹, which can be rotated about the asymmetrically arranged axle 24². With the aid of this plate the blowing air which is uniformly distributed in the inlet end of the passage, may be uniformly or non-uniformly distributed at the moment of issue over both of the outlet portions. Consequently it is possible, as desired, to allow a larger quantity of air to flow through the upper or lower outlet portion or to give it a direction which is inclined more upwards or downwards without wholly shutting up the other outlet portion.

A ledge 21¹ separating the streams of material is placed on the upper shaking box of the winnowing mechanism 21 at the plane of contact between the zones I and II and also, if desired, at the plane of contact between the zones II and III. These ledges or partitions may be detachably arranged. 25 denotes a passage which catches the preliminary winnowed grains and leads to an elevator 26.

A second preliminary winnowing mechanism 27, likewise consisting of two oppositely running shaking boxes movably mounted transversely of the longitudinal axis of the machine, is located below or behind the hood 13. A two-armed swinging lever 22¹ provided on each side of the box is mounted on a pivot 22². Its shorter lower arm directly engages the lower box of the shaking apparatus whilst its longer upper arm is connected with the upper box by means of a connecting rod. The upper box is suspended in front and behind on springs 22 whilst the lower box rests in front on supporting springs and is carried at its rear end by the reciprocating levers. The position of attachment of the connecting rod 23 pivoted to the blower shaft 16, to the reciprocating lever may be made changeable. The use of reciprocating levers as a portion of the driving mechanism in the case of these winnowing machines, renders it possible to impart to each box a stroke corresponding to its working requirements without the necessity of making adjustments on the common driving shaft 16. The preliminary winnowing apparatus 27 is aerated by the rear single blower 18 and is, if necessary, also adapted to be regulated. The preliminarily winnowed grains fall onto a return floor and pass through the passage 28 to the elevator 26.

The latter is carried to such a height between the blower portions 17 and 18 that it can deliver the grains into a drum 29 which lies above the machine frame 6 parallel to the longitudinal axis of the machine and which serves as an awning and conveying device and moves the grains into

the cleaning mechanism 30 located behind the hood 13 above the preliminary winnowing mechanism 27. In beardless corn is being thrashed, the grains are fed to the cleaning mechanism 30 by a conveying device 29¹.

The cleaning mechanism consists of a single shaking box which is movable transversely to the longitudinal axis of the machine and is suspended on vertical springs and which is aerated by a blower 31 arranged at the end of the awning device. It is driven by a jolting rod 30¹ which is attached to the connecting rod 23 and which 10 imparts to it a smaller stroke than that imparted to the upper box 27. The sifted corn is collected on the floor 32 and passed to the carrying off outlet 33. Grains or ears that blow over, fall at the end of the 20 floor 32 into a rearwardly directed hopper 34 which leads them to the upper shaking box of the rear preliminary winnowing apparatus 27. Here it falls onto a surface which is partitioned off by a ledge 27¹ and which thus remains free from the short straw coming from the hood 13. In this manner all the grains blowing over are subjected to repeated winnowing and arrive in the elevator in a short simple way or pass 30 on to repeated further treatment. 35 represents the drive of the awning of conveying device 29, 29¹ from the carrying off elevator 26.

The machine operates as follows:

35. The grain to be thrashed is fed through the inlet 14 to the beaters 3 which seize it and lead it travelling through a helical path axially through the machine up to its discharge end. In doing this, it is de-grained principally by being hurled against the fixed abutments 5, whilst in zone II it undergoes, on account of the increasing proximity of the members 3, 5 a sharper treatment which approaches reduction and which changes in 45 zone III into a disintegrating action of the desired degree.

In accordance with this mode of treatment there issues, through the sieve-like bottom portion of the drum 4 and from the bottom opening of the hood 13, a stream of material which can be regarded as composed of single streams which lie axially behind one another and which consist in the inlet zone substantially only of grains but which, on passing 50 towards the rear end of the machine, carry with them more and more impurities and at the discharge end contain almost entirely short straw.

By means of this novel arrangement of 55 blower and beater drum, the individual streams of material can now be treated directly side by side and transversely to the longitudinal direction of the machine, a feature which is extraordinarily advantageous 60 because the said streams are directly and

by themselves individually exposed to the wind current and are more thoroughly winnowed on account of the avoidance of the formation of large mixed streams of material. The effect of this divided or stepwise treatment of the material to be winnowed is enhanced by the movement transversely of the longitudinal axis of the machine, of the shaking boxes which convey the material to be sifted approximately in a straight line, so that without the arrangement of special walls on the sieves, the streams of material to be sifted remain side by side separated and parallel to each other.

Naturally, special circumstances may make it appear advisable to provide one or a number of separating walls. The ledge 21¹ represented with the front preliminary winnowing apparatus has thus the object of separating, in the case of grain with sharp ear portions which become detached in the inlet zone and are not usable as cattle food, the said ear portions completely from the remaining short straw and to bring them to the notice of the operator.

The short straw issuing from the hood 13 meets a sharply blowing wind current of the machine which sucks up any necessary additional operating air through the attachment 12. The wind current loosens the straw falling on the rear preliminary winnowing apparatus 27 and distributes it over the sifting surface which is entirely aerated by the blower 18.

The grains sifted off in the preliminary winnowing devices 21 and 27 reach the elevator 26 which conveys them either into the driver 29 acting as awning device or into the conveying device 29¹ from either of which they pass into the cleaning mechanism 30. The cleaned grains are carried off at 33. The aeration of the cleaning mechanism 30 is effected by the blower 31 arranged at the end of the awning device 29. The portions of the material blown over arrive through the passage 34 on the sifting surface of the upper shaking box which is partitioned off by the ledge 27¹. The invention is also applicable to a machine used for threshing only or to a machine used for reducing only since even in the latter instance the materials may be sorted out into several streams.

What I claim is:

1. The combination of an axial thrashing machine including means for gradually reducing the straw and having a thrashing drum with a grain outlet and an axially spaced combined reduced straw and grain outlet with a winnowing apparatus operatively associated therewith and projecting underneath the drum, the said winnowing apparatus comprising axially and successively positioned independently functioning cleaning and separating means extending transversely to the longitudinal direction of

the drum and being positioned closely adjacent the outlets of the drum to which they correspond and with which they communicate to separately receive the different 5 grades of materials as they come from the axial machine and to treat them in transverse direction to the machine casing.

2. In an axial machine of the character set forth in claim 1 wherein the said winnowing apparatus comprises a blower whose outlet is arranged adjacent the openings in the drum through which the material to be cleaned is delivered for delivering blower air directly to the material as the same 10 leaves the casing and before it reaches the winnowing stages.

3. In an axial thrashing machine a casing enclosing a thrashing chamber and a straw reducing chamber having a grain inlet at 20 one end and an outlet for reduced straw at the other end, openings for the delivery of material to be cleaned of different degrees of cleanliness axially arranged behind each other in the bottom of the drum, said drum being mounted in longitudinal direction of the machine, separating apparatus underneath said drum in a transverse direction thereof consisting of at least two winnowing 25 mechanisms each with sieves shaking transversely to the thrashing drum, said mechanisms axially arranged one behind the other for the separate treatment of streams of said material and the reduced straw, a blower whose shaft is arranged parallel to the 30 thrashing drum.

4. An axial machine of the character set forth in claim 3 wherein the blowers are arranged opposite the independently moved shaking sieve-units and to one side and below the level of the thrashing drum together with comparatively short wind delivery 40 channels leading from said blowers to points in proximity to the bottom delivery openings of the thrashing drum arranged axially one behind the other and ending in front of said shaking sieves.

5. An axial machine of the character set forth in claim 3 wherein a winnowing blower is provided for each of said winnowing 50 mechanisms, said blowers being of different capacity.

6. An axial machine of the character set forth in claim 3 including a blower for each of said winnowing mechanisms, the blower 55 for the winnowing mechanism at the delivery end of the machine corresponding to the straw outlet, being of greater size and adapted to supply a larger quantity of air than the blower near the admission end.

7. In an axial thrashing machine, a 60 thrashing drum having openings situated axially one behind the other as passages for the outlet of material to be cleaned of different degrees of cleanliness, a winnowing apparatus underneath and beside said thrashing

drum consisting of at least two winnowing mechanisms shaking transversely to the drum and being axially arranged one behind the other adapted for the separate treatment of the streams of material, a blower for each 70 of said winnowing mechanism having a common shaft disposed parallel to the thrashing drum and connected to said shaking mechanisms.

8. In an axial thrashing machine, a 75 machine drum having in its wall openings axially arranged one behind the other and forming outlets for the material to be cleaned of different degrees of cleanliness, a winnowing apparatus underneath said 80 thrashing drum comprising at least two preliminary shaking mechanisms arranged axially the one behind the other and transversely to the thrashing drum, a blower for said mechanisms whose shaft is disposed 85 parallel to the axis of said thrashing drum, an elevated aerated oscillatable final cleaning mechanism in the corner of the delivery end of said thrashing drum and a shaking mechanism, a lifting means situated between said winnowing mechanisms and adapted to lift the preliminarily cleaned grain up to the height of said last named mechanism and a conveying device to convey the grain to said final cleaning mechanism.

9. A machine of the character set forth in claim 8 wherein are provided a conveying drum acting at the same time as an awning device and a drum containing a worm-like conveying device between said lifting means and the cleaning mechanism, a blower arranged at the end of one of the drums, said blower being co-ordinated with the final cleaning mechanism at the delivery end of the thrashing drum.

10. In a machine of the character set forth in claim 1 wherein the winnowing apparatus includes a shaking sifter, the latter being provided with a partition extending in a direction at an angle to the axis of the thrashing drum for separating the materials of different grades.

11. In an axial thrashing machine a casing enclosing a thrashing chamber and a straw reducing chamber, said chamber having a grain inlet at one end and an outlet for reduced straw at the other end and openings in the bottom portion thereof arranged axially one behind the other for the delivery of streams of materials of different degrees of cleanliness and a winnowing apparatus disposed essentially beneath the casing and comprising axially and successively arranged shakers disposed transversely to the axis of the casing and adapted to be moved independently of one another, part of the shakers being provided for the outlets of the grain streams and another part for the outlet of the reduced straw.

12. In an axial thrashing machine a cas-

ing enclosing a thrashing chamber and a straw reducing chamber, said casing having a grain inlet at one end and an outlet for reduced straw at the other end and openings in the bottom portion thereof arranged axially one behind the other for the delivery of streams of material of different degrees of cleanliness and a winnowing apparatus disposed essentially beneath the casing and 5 comprising axially and successively arranged shakers disposed transversely to the axis of the casing and adapted to be moved independently of one another, each shaker having oppositely moved sieve-boxes, part of the 10 shakers being provided for the outlets of the grain streams and another part for the outlet of the reduced straw.

13. An axial thrashing machine for thrashing and reducing grain, comprising 20 a casing arranged in the longitudinal direction of the machine, a grain inlet at one end and an outlet for reduced straw at the other end of the casing, a rotary shaft within the said casing, working members secured to the 25 said shaft, corresponding working members provided within the said casing, the said casing having axial outlets arranged one behind the other for grain of different degrees of impurity, a winnowing apparatus for grain 30 and reduced straw essentially arranged beneath the thrashing and reducing casing, and a blower forming part of the winnowing apparatus and being disposed parallel to the thrashing and reducing casing.

35 14. An axial thrashing machine for thrashing and otherwise treating grain, comprising a casing arranged in the longitudinal direction of the machine, a grain inlet at one end and a straw outlet at the 40 other end of the casing, a rotary shaft within the casing, working members secured to the said shaft, corresponding counter-members provided at the inside of the casing, the said casing having axial outlets arranged 45 one behind the other for streams of cleaning material of different degrees of impurity, shakers moved transversely to the casing and axially disposed one behind the other essentially underneath and near the outlets of the streams of material to be cleaned 50 for the separate treatment of these streams, and a blower forming part of the shakers and disposed parallel to the thrashing casing.

55 15. A machine of the character set forth in claim 14 wherein one shaker unit is provided for the straw outlet at the end of the casing and for a separated portion of the blower.

60 16. A machine of the character set forth in claim 14, wherein each shaker has superposed sieves, a wedge-shaped wind distributing and regulating device arranged in the blower outlet, the said wedge-shaped body 65 being secured to, and adjustable solely by,

a shaft disposed on an edge facing the shaker.

17. In an axial thrashing machine, a machine drum having in its wall openings axially arranged one behind the other and forming outlets for the material to be cleaned of different degrees of cleanliness, a winnowing apparatus underneath said thrashing drum comprising two preliminary shaking mechanisms arranged axially the 70 one behind the other, a blower for said mechanisms whose shaft is disposed parallel to the axis of said thrashing drum, an elevated aerated oscillatable final cleaning mechanism at the delivery end of said 75 thrashing drum, a lifting means situated between said winnowing mechanisms and adapted to lift the preliminarily cleaned grain up to the height of said last named mechanism and a conveying device to convey the grain to said cleaning mechanisms, a channel being provided and connected to the overflow of said final cleaning mechanism and leading downward to the shaking sieve of the rear winnowing mechanism, the 80 latter extending over the delivery end of the thrashing casing and the channel terminating on a portion of the projecting shaking sieve of the winnowing mechanism.

In testimony whereof, I have signed my 85 name to this specification.

FELIX SCHLAYER.
